No. 833,362.

PATENTED OCT. 16, 1906.

M. S. WRIGHT.
AUTOMATIC MUSICAL INSTRUMENT.
APPLICATION FILED APR. 7, 1902.

UNITED STATES PATENT OFFICE.

MORRIS S. WRIGHT, OF WORCESTER, MASSACHUSETTS, ASSIGNOR TO
AEOLIAN COMPANY, A CORPORATION OF CONNECTICUT.

AUTOMATIC MUSICAL INSTRUMENT.

No. 833,362.

Specification of Letters Patent.

Patented Oct. 16, 1906.

Application filed April 7, 1902. Serial No. 101,624.

To all whom it may concern:

Be it known that I, MORRIS S. WRIGHT, a citizen of the United States, residing at Worcester, in the county of Worcester and 5 Commonwealth of Massachusetts; have invented a new and useful Improvement in Automatic Musical Instruments, of which the following is a specification, accompanied by drawings forming a part of the same, in 10 which—

Figure 1 represents a vertical sectional view of a structure embodying my invention and representing in side elevation the air and valve chambers of a pneumatic action adapted to operate the keys of a musical instrument. Fig. 2 is a top or plan view shown in section on line 2-2, Fig. 1. Fig. 3 is a horizontal sectional view on line 3-3, Fig. 1, and Fig. 4 is a perspective view of the link between the finger or key-striker and its actuating mechanism.

Similar reference-figures refer to similar parts in the different views.

My invention relates to an automatic musical instrument, and particularly to that part by which one or more of a series of keys are operated by a pneumatic actuating mechanism controlled by a moving strip of perforated paper; and my invention consists in 25 the construction and arrangement of parts, as hereinafter described, and pointed out in the annexed claims.

The pneumatic actuating device embodying my invention is similar in its main features and principle of operation to similar devices now in common use which embody a vacuum-chamber from which air is withdrawn by a bellows or other suitable device, a primary pneumatic or valve-operating diaphragm with an air-passage controlled by perforated paper to operate the valve, and a main pneumatic or finger-actuating diaphragm. These elements are common in pneumatic actuating devices; and my present 35 invention relates to the construction and arrangement of the several parts by which the device is rendered more compact and simple in its construction; and it further relates to the employment of a series of hinged fingers or key-strikers, which are capable of being folded from their operative or extended position into a compact position within the case when the apparatus is not in use, with means

for simultaneously lifting the pivoted fingers or key-strikers into their operative position. 55

Referring to the accompanying drawings, 1 denotes an outer case inclosing the actuating mechanism.

2 2 denote rolls for carrying the strip of perforated paper and having means (not shown) for rotating the rolls, by which the paper is moved over the edge 3 of a tracker-board 4. The edge of the tracker-board is provided with a series of openings 5, which are alternately opened and closed by the movement of the perforated paper, said openings communicating with air-channels, one of which is shown at 6.

The air-channel 6 passes downward through a channel-board 7 and communicates at its lower end with an air-space 8 beneath a primary pneumatic or valve-actuating diaphragm 9. Placed immediately behind the channel-board 7 is a horizontal valve-board 10, having its rear edge abutting against the side of the channel-board 7. The valve-board 10 is provided at the edge next the channel-board with valve-chambers, one of which is shown at 11, containing a valve-stem 12, which extends downward below the valve-board and is mounted on a follower 13, attached to a diaphragm 9 over the air-space 8, so that a rising-and-falling movement will be given to the valve-stem by the movement of the diaphragm 9. The valve-stem 12 carries an upper valve 14 and a lower valve 15, the upper valve 14 being arranged to close an air-passage 16, connecting the valve-chamber 11 with the open air, and the valve 15 controlling an air-passage 17 between the valve-chamber 11 and an inclosed pneumatic chamber 18 above the diaphragm 9.

The pneumatic chamber 18 extends across the apparatus beneath the valve-chambers 11 and is provided with a restricted vent-passage 19, communicating with the air-channel 6, and it also is provided at its end with an opening 20, communicating with an air-conducting passage 21 in the conductor-board 21^a, Fig. 3, leading to a bellows or other suitable device for withdrawing air from the pneumatic chamber 18, and thereby reducing the air-pressure therein. The bellows is not shown in the present drawings, as its construction and use will be well understood by those conversant with this class of mechan-

isms. The valve-chamber 11 communicates at its rear end directly with a larger chamber 22, having its upper side covered by the finger-actuating diaphragm 23, said chamber 22 and diaphragm 23 forming the main operating-pneumatic in contradistinction to the smaller or primary pneumatic consisting of the diaphragm 9.

To the under side of the diaphragm 23 is attached a follower 24, provided at its central portion with a block or rib 25, adapted to strike the cranked inner end 26 of a rock-shaft 27, journaled in a post 28 within the air-chamber 22 and in a stuffing-box in the end wall of the chamber. The rear projecting end of the rock-shaft 27 is provided with a crank-arm 29, connected by a link 30 with a lever 31, and between the levers 31 and the lever-board 33 is a blade-spring 34, which serves to maintain the lever 31 in its raised or normal position, from which position it is lowered or depressed by the action of the crank-arm 29 and link 30. The opposite end of the lever 31 is provided with a hinged finger or key-striker 35, carrying at its free end a tip 36, arranged to rest upon a piano-key 37 and having at its opposite end a projection 38, preferably bent at right angles and extending over the top of the lever 31 and receiving on its upper side the pressure of a blade-spring 39, by which the projection 38 is held against an adjusting-screw 40 in order to enable the hinged finger or key-striker 35 to be adjusted relatively to the lever 31. The lever-board 33 is provided at its opposite ends with brackets, one of which is shown at 41, Figs. 1 and 2, in which is journaled the cranked rod 42, normally held by gravity in a vertical position, as shown in Fig. 1.

When the apparatus is removed from the piano or other keyed instrument, the door 43 upon the back side of the case is opened and the hinged fingers or key-strikers 35 are swung downward into the case in the position shown by broken lines 35^a, allowing the door 43 and the supplementary door 43^a hinged thereto to be closed; but when the apparatus is to be applied to the piano the hinged extensions or key-strikers 35 are all simultaneously raised by swinging the crank-rod 42 into the position shown by broken lines 42^a, Fig. 1, when the door 43 is again closed and the door 43^a left open, the crank-rod 42 then resting upon the upper edge of the door 43, as shown at 42^b, allowing the fingers or key-strikers 35 to be depressed.

The finger-board 33 is pivoted at each end upon uprights attached to the ends of the board 10, one of said uprights being shown at 44, Figs. 1 and 2, and the opposite or forward edge of the board, upon which the lever 31 is hinged, is adjusted vertically by means of an adjusting-screw 45, engaging a nut 46, held in the lever-board and having its lower end provided with a neck 47, journaled in a

bracket 48, attached to the valve-board 10, by which the screw is held from longitudinal movement and enabled by its rotation to raise or lower the forward edge of the finger-board, swinging it upon its pivots 49 for the purpose of raising or lowering the fingers or key-strikers 35 relatively to the piano-keys. The levers are therefore adjusted simultaneously by the action of the adjusting-screw 45, and each finger or key-striker is likewise capable of independent adjustment by varying the length of the link 30, and to accomplish this I form the lower section of the link of a wooden block 50, provided with a transverse round hole 50^a to hold a leather nut 50^b, into which is screwed a screw-threaded wire 51, provided with a ring 52 at its upper end, which rests against a washer 53 upon the upper surface of the lever 31. The levers 31 are rounded at their ends 32 and are held between washers 32^a and 32^b by a screw 32^c, which allows the lever to swing in both a vertical and a horizontal plane. The lever is held from lateral movement by means of the upright wires 54, held in the lever-board 33 and extending upwardly upon opposite sides of the levers.

The valve-board 10 has a series of chambers, finger-actuating diaphragms, valves, and valve-actuating diaphragms duplicates 95 of those above described, and beneath the valve-board 10 are similar valve-boards, one of which is indicated at 52, Fig. 1, with their respective chambers arranged in different vertical planes. This feature is, however, now commonly practiced and forms no part of my present invention, which relates solely to the single valve-board and its connected parts, by which the apparatus is rendered much more compact and simple in construction and less liable to become inoperative by reason of climatic changes.

What I claim as my invention, and desire to secure by Letters Patent, is—

1. In an automatic musical instrument, 110 the combination of an air-chamber having an opening in its top, a flexible diaphragm closing said opening, a follower attached to the under side of said diaphragm, a rock-shaft journaled in said air-chamber and extending through the wall of the chamber and operatively connected at its inner end with said follower, a key-striker operatively connected with the opposite or outer end of said rock-shaft, a board pivoted at one end and having a pivotal connection at its opposite end with the pivoted end of said key-striker and means for rocking said board on its pivot. 115

2. In an automatic musical instrument, 120 the combination of an air-chamber having an opening, a flexible diaphragm closing said opening, a follower attached to said diaphragm, a key-striker pivoted at one end, intermediate connecting mechanism between said diaphragm and said key-striker, a board 125

pivoted at one end and having a pivotal connection at its opposite end with the pivoted end of said key-striker, and means for gradually adjusting said board on its pivot.

5. 3. In an automatic musical instrument, the combination with a key-striker, of a board pivoted at one edge and having a pivotal connection with one end of said striker at its opposite edge, and means for rocking 10 said board on its pivot, substantially as described.

4. In an automatic musical instrument, the combination of a board pivoted at one edge, a key-striker pivotally connected to the 15 opposite edge of said board, and an adjusting-screw by which said board is rocked on its pivot, substantially as described.

5. In an automatic musical instrument, the combination of a board pivoted at one edge, a key-striker pivotally connected to 20 said board, means for adjusting said board to raise and lower said key-striker, a spring between said board and said key-striker, and

means for depressing said key-striker against the tension of said spring, substantially as 25 described.

6. In an automatic musical instrument, the combination of a key-striker having a pivotal connection with the supporting-framework by means of a rounded end, and a 30 pair of washers placed on opposite sides of said rounded end, and a screw by which said washers are held in place, substantially as described.

7. The combination with a hinged lever, of 35 a key-striker pivoted to one end of said lever and having a projection extending over said lever, an adjusting-screw held in said lever and bearing against said projection, and a spring by which said projection is held against 40 said screw, substantially as described.

Dated this 4th day of April, 1902.
MORRIS S. WRIGHT.
